ICE VENDING MACHINE

John H. Schreiber, St. Louis, Mo.

Application January 23, 1933, Serial No. 653,038

26 Claims. (Cl. 312—35)

This invention relates to vending machines, having special relation to machines adapted and designed for use as ice vending machines.

Objects of the invention are to provide an improved vending machine adapted for installation in a special cabinet or housing forming the complete supporting structure of the machine; to provide a simplified and inexpensive mechanism easily accessible for inspection, repairs and interchange of parts; to provide a mode of operation, including a one-way movement of the parts eliminating reciprocating actions and movements, and to simplify the filling of the magazines; to provide an easily operated mechanism requiring a small amount of power for discharging and reloading, and to avoid the hoisting and raising of the ice cakes by operation of the mechanism; to arrange the magazines for the respective ice cakes along the wall and thereby provide storage and loading space on the inside of the machine; to utilize the floor and the ceiling of the housing as frames to support the mechanisms and the magazines; to provide a shifting of the magazines to obtain a space through which a person may enter and leave the machine; to provide improved operating mechanism for imparting a rapid movement to the series of magazines at the unloading point and to reduce speed of movement of the unloaded magazine to a place at the rear of the series of magazines within the housing; to provide means for holding wrapped or unwrapped ice cakes on the supports and for discharging such ice cakes through the discharge outlet; to provide an air space between the top of the cabinet and the roof for circulation of the air and, if desired, for propelling the air through this air space; and to construct the machine in circular arrangement, whereby the magazines move in a circular course, thus diminishing the expense and providing a machine that will operate more efficiently, easily and satisfactorily.

Other objects and advantages of this invention will be readily apparent from the following detailed description, reference being made to the accompanying drawings, in which—

Fig. 1 is a horizontal sectional view of a preferred form of my invention.

Fig. 2 is a diagram graphically illustrating the sequence of operation of the machine.

Fig. 3 is a vertical sectional view on the line 3—3 of Fig. 1 of the machine taken through the discharge outlet.

Fig. 4 is a vertical sectional view on the line

4—4 of Fig. 1 at right angles to the section of Fig. 3.

Fig. 5 is an enlarged view showing the discharge mechanism and the mechanism for unloading the magazines.

Fig. 6 is an enlarged vertical sectional view on the line 6—6 of Fig. 5.

Fig. 7 is an enlarged vertical sectional view on the line 7—7 of Fig. 4.

Fig. 8 is an enlarged detail view looking in the direction of the line 8—8 of Fig. 5.

Fig. 9 is an enlarged sectional view on the line 9—9 of Fig. 4.

Fig. 10 is a diagrammatical view showing an oval arrangement of the magazines as distinguished from an approximately circular arrangement.

The cabinet or housing enclosing the vending mechanism comprises a bottom wall or floor 1 from which rises a circular enclosing wall 2 supporting a top wall 3. The bottom wall or floor 1 and the top wall 3 support the operating mechanism. A circular track 4 is mounted rigidly on the bottom wall 1 in axial alignment with a similar circular track 5 attached to the top wall 3 of the housing.

A circular series of unattached upright supports 6 have endwise abutting bars 7 (Figs. 1, 4, and 5) attached to their lower ends, and similar endwise abutting bars 8 attached to their upper ends. A pair of grooved rollers 9 are rotatively connected with the bars 7 and operate along the circular track 4, and rollers 10, rotatively connected with the bars 8, engage the track 5 and cooperate to hold the upright supports 6 in proper upright position for circular movement along the tracks 4 and 5.

Each of the supports 6 has along its forward edge a flange 11 and a series of magazines is attached to each support 6. In the specific embodiment shown, there are eight of these magazines, each comprising a bottom portion 12 and an upstanding flange 13 along the forward edge of the part 12. These magazines are spaced vertically and each magazine is designed and adapted to receive and support a cake of ice 14 held from sliding inwardly from the magazines by beads 15 along the inner edges of the respective magazines. Or, each magazine may be provided

with an upstanding flange 16 along its inner end over which the ice cake 14 must be passed in order to load the respective magazines. The distance between the upper edge of each flange 16 and the next upwardly adjacent magazine 12 measures or determines the maximum size of

5

a cake of ice that may be passed onto the magazines. Accordingly, when any block of ice is passed over the flange 16 and becomes seated on the magazine 12, a space 17 is left between the 5 upper surface of the cake of ice and the under side of the next upwardly adjacent magazine.

One side of the cabinet or housing wall has a discharge opening 18 opened and closed by a sliding door 19 and having an outwardly extended discharge chute 20.

A vertical shaft 21 is supported for rotation by the bottom wall 1 and top wall 3 of the housing and is driven by a motor 22 through gearing 23 (Fig. 7). Duplicate mechanisms are 15 driven by the lower and upper ends of the shaft 21. The description of one of these mechanisms constitutes a description of the other, and the same reference numerals are applied to analogous parts of said mechanisms wherever they 20 appear in the drawings.

Each of said mechanisms comprises a sprocket wheel 24 attached to the shaft 21 and engaged by a sprocket chain 25, which also engages an adjacent sprocket wheel 26 mounted on a stud 25 shaft 27. A sprocket wheel 28 is rigid with each of the sprocket wheels 26, there being, as stated, one sprocket wheel 26 and its attached sprocket wheel 28 at the bottom of the machine and one of each of said wheels at the top of the machine. 30 Sprocket chains 29 engage the sprocket wheels 28. The outer portions of the sprocket chains 29 operate against curved guides 30 and said chains engage sprocket wheels 31 supported on stud shafts 32 at the top and bottom of the housing 35 and also engage sprocket wheels 33 on stud shafts 34 and sprocket wheels 35 on stud shafts 36. The directions of rotation of the sprocket wheels 28, 31, 33 and 35 are indicated by the arrows applied thereto in Fig. 5 of the drawings. An arm 37 is 40 rigid with one of the links of the chain 29.

Sprocket chains 38, of similar construction to the sprocket chains 29, engage sprocket wheels 39 and 40, respectively, at the top and bottom, and also engage the sprocket wheels 41 rotative 45 on stud shafts 42 at the top and bottom of the housing. An arm 43 (Fig. 1) is rigid with one of the links of the chain 38.

It is now clear that the motor 22 drives the chains 29 and also the chains 38 and that, due to 50 the ratio of the gearing, the chains 29 are driven at considerably greater speed than the chains 38. These chains 29 and 38 have definite stopping and starting positions, and these positions are shown in Fig. 1 of the drawings. As there shown, 55 a projection 44 is rigid with and extends inwardly from each bar 7 and each bar 8 in position to be engaged by the adjacent arm 37 after said arm 37 moves a very slight distance from its stopping and starting position. The movement of the 60 chain 29 being in the direction of the arrow 45 (Fig. 5), it is apparent that the arms 37, by engaging the projections 44, will move the magazine support 6 around to the position on the magazine support shown by dotted lines in Fig. 5, at which 65 time the arms 37 will pass beyond and escape from the projections 44 while the chain 29 continues in motion. During the entire movement of the chain 29, the chain 38 is operating and, about the time that the arms 37 pass beyond 70 and escape from the projections 44, the arms 43 on the chains 38 engage said projections 44 and move the emptied magazines forwardly one step. This causes the bars 7 and 8 on the emptied magazine support 6, indicated by dotted lines in 75 Fig. 5, to abut against the rear ends of the cor-

responding bars 7 and 8 of the next forwardly adjacent magazine and move the circular series of magazines forwardly one step to bring another magazine in position to be engaged and operated by the arms 37.

The motor 22 is controlled by any appropriate start and stop mechanism, or otherwise as may be desired, in order to stop the chains 29 and 38 in their definite stopping and starting positions, in which the arms 43 have just passed from engagement with the projections 44 and another magazine with its projections 44 has been moved to position for operation by the arms 37.

An intermittently operated motor 46 drives a pinion 47 meshing with a gear wheel 48 attached 15 to a rotary shaft 49. A pinion 50 (Figs. 4 and 8) is attached to the shaft 49 and meshes with a gear 51 attached to a rotary shaft 52. A Geneva movement member, comprising a disc 53 and an arm 54, is attached to the shaft 52. The arm 20 54 projects radially opposite the arcuate notch 55 (Fig. 7) in the disc 53. The arm 54 supports a roller 56 adapted to engage a cooperating Geneva movement member 57 mounted for rotation on a support 58 and having a number of 25 radial slots 59 and intermediate peripheral arcuate notches 60. When the respective slots 59 are engaged by the roller 56, the member 57 is rotated 90° for each complete revolution of the member 53. The notches 60 engage the peripheral portion of the disc 53 while the extended portions of the member 57 having therein the slots 59 are received in the notch 55, thus permitting the Geneva movement and the locking of the member 57 during the time that the disc 53 30 is turning 270° or three-fourths of a complete revolution. A gear wheel 61 is rigid with and rotated by the Geneva member 57 and meshes with a gear 62 attached to a rotary shaft 63.

A pair of spaced sprocket wheels 64 are attached to the shaft 63 and are engaged by sprocket chains 65, which also engage idler sprockets 66 mounted on stud shafts 67 near the bottom 1.

A series of angular shelves 68 are pivoted to 45 the chains 65 and are spaced apart approximately the same distance as the magazines 12. Each shelf 68 has a pair of arms 69 projecting angularly therefrom and equipped with rollers 70, which, during descent of the shelves and in the 50 descending positions of the shelves, operate between the side flanges of vertical channel bars 71 (Figs. 5 and 6) and thereby support the shelves 68 in approximately horizontal positions. Below the lower ends of the channel bars 71, angle bars 72 are pivotally supported in vertical continuation of the channel bars 71 and the rollers 70 passing from the channel bars 71 engage the inwardly extended front angles of the angle bars 72. The upper ends of the angle bars 72 are 55 swung forwardly at the proper time, permitting the lowest shelf 68 to incline downwardly and forwardly, as shown in Fig. 6 of the drawings, and thereby facilitate and expedite the movement of the ice cake 14 therefrom. The angle bars 72 are mounted on pivots 73 (Fig. 9) and are connected by links 74 with depending arms 75 attached to a rockable shaft 76. An arm 77, attached to the shaft 76, is connected by a link 78 with an arm 79 mounted on a pivot 80 and having a roller 81 operating in a cam groove 82 formed on the outer surface of the gear wheel 84. In the starting position of the cam 82, the arm 79 is held in its raised position and thereby, through the connections 78, 77, 75, and 74, the 75

angle bars 72 are positively held in alignment with the channel bars 74, so that the lowest shelf 68 will be supported horizontally to retain the ice cake 14 thereon. After the cam 82 turns a sufficient distance, the arm 79 is thereby moved downwardly, operating the connections 78, etc. to swing forwardly the angle bars 72 (Fig. 6) and thereby permit the lowest shelf 68 to incline downwardly and outwardly and permit the ice cake 14 to be moved outwardly through the opening 18 onto the discharge chute 20.

A pinion 83 (Figs. 4, 8, and 9), rigid on the shaft 49, meshes with the pinion 84 on the upper end of a vertical rotary shaft 85. A pinion 86, attached to the lower end of the shaft 85, meshes with a pinion 87 on the inner end of a horizontal rotary shaft 88. A pinion 89 is attached to the forward end of the shaft 88 and meshes with a pinion 90 attached to a horizontal shaft 91. Discharge members 92 are attached to the shaft 91 (Figs. 1 and 6). The members 92 may have teeth for discharging unwrapped ice cakes and may be devoid of teeth and function as frictional rolls to discharge wrapped cakes of ice. When the shelf 68 drops to the inclined position shown in Fig. 6, these discharge members are received in slots 93 in the magazine element. The members 92 raise the ice cake from the retaining elements 94, which may be either projections to indent into the ice or frictional elements, such as rubber, to engage the wrappers of wrapped ice cakes. The rotating members 92 propel the ice cake 14 outwardly through the opening 18 onto the inclined chute 20.

At the proper time, the shaft 63 is rotated by operation of the Geneva gearing, by the devices 53, 56 and 57 and by the gears 61 and 62, thereby operating the chains 65 a distance equal to the distance between two adjacent shelves 68. This moves rearwardly the lowest shelf 68 from which the ice cake had been discharged to the position of the lowest vacant shelf 68, shown in Fig. 6, the forward end of the shelf being supported in this position by a member 95. These operations are repeated until the ice cakes are discharged from all of the shelves 68, after which all of said shelves are reloaded.

During their upward movement, the shelves 68 extend downwardly, because the rollers 70 are out of engagement with any guiding members. As the shelves move over the shaft 63, the arms 69 engage said shaft 63 and swing the shelves through the arc 96 (Fig. 6) until the uppermost shelf is extended forwardly and supported horizontally by engagement of the rollers 70 with the guides 71. This operation should be clearly apparent from Fig. 6 of the drawings.

A cord or cable 97 has one end attached to a fixed member 98 (Figs. 7, 8, and 9) and its opposite end attached to a latch 99 mounted on a pivot 100 supported by the sliding door 19 movable vertically in guides 102 to open and close the outlet opening 18. In the closed position of the door 19, a spring 103 holds the latch 99 in latching position in a notch 104 in the wall 2. The cord or cable 97 engages a roller 105 supported by an arm 106 mounted on a pivot 107 and having a roller 108 operating in a cam 109 on the inner side of the gear wheel 51. The cord or cable passes upwardly over supporting rollers 110 supported by the top wall 3 and thence downwardly to engagement with the latch 99. In the starting position of the cam 109, the arm 106 is supported in its upper position, the door 19 is in its downward and closed position and the latch 99

is engaged in the notch 104, which is inaccessible from the outside, thus making it impossible for the door 19 to be opened in an unauthorized way. Just before the lowest ice cake 14 starts to move outwardly, the cam 109 moves the arm 106 downwardly, thereby operating the cord or cable 97, first to disengage the latch 99 from the notch 104 and then to move the door 19 upwardly to open position, after which the ice cake 14 is discharged outwardly, as described.

During movement of the front series of magazines 12 by operation of the chains 29, which movement is effected by the moving arms 37 engaging and moving the projections 44 and thereby the corresponding series of magazines, the ice cakes 14 on said series of magazines are placed on the selves 68, immediately above which are the magazines. The magazines are shown in broken lines in Fig. 9 and the shelves 68 are shown in solid lines, it being apparent that the magazines move above the shelves. During this forward movement of the magazines, the ice cakes are stopped by rigid arms 111 projecting into the path of movement of the ice cakes, but not interfering with the movement of the magazines. 12. 25

A door opening 112 (Figs. 1 and 4) is equipped with a door 113 mounted on hinges 114 and provided with a latch and lock device 115, whereby the door may be held closed. This door constitutes an entrance and exit through which a person may enter and leave the housing for any needed purpose. For instance, it may be desired to enter the housing to lubricate or adjust parts of the mechanism, or to load the magazines with ice cakes. The central part of the housing, 30 around which the magazines travel, affords considerable space in which cakes of ice may be stored.

The housing may be provided with a roof 116 (Fig. 3) mounted above the top wall 3 to provide 40 an intervening space 117 for the circulation of air across the top of the housing for cooling purposes. Forced circulation of the air may be effected by a blower or fan 118 operated by a machine 119, or otherwise as desired. The machine 45 119 includes a compressor or pump to effect compression of a refrigerant in the refrigerating coils 120 mounted in the upper part of the housing to maintain a reduced temperature in the housing and prevent the ice from melting. Operation of 50 the compressor or pump may be controlled by any familiar thermostatic switch device, such equipment and the use and installation thereof and the manner of installing and using the same being well known.

It is my intention to equip this machine with appropriate coin controlled switch mechanism for controlling operation of the motor 46, so that when a coin of proper value is placed in the switch mechanism, the motor 46 will be operated 60 from and to its starting position. Each such operation of the motor 46 rotates the Geneva driving member 53 one complete revolution and thereby rotates the driven member 57 90°. This 90° movement of the driven member 57 imparts a 65 turning movement to the shaft 63 and thereby operates the chains 65 to move the shelves 68 downwardly one shelf space.

The gear 51, being rotated by the motor 46, causes the cam 109 to move the arm 106 downwardly and operate the cord or cable 97 and unlatch and open the door 19 by a comparatively quick movement. Thereafter in proper time sequence, the cam 82, through the connections 18, etc., swings the angle bars 72 forwardly to per- 75

mit downward tilting of the lowest shelf 68, causing the members 92 to disengage the ice cake 14 from the holders 94 (Fig. 6). The members 92 are rotated by the motor 46 through the driving 5 gearing, terminating in the pinions 89 and 90 (Fig. 9), and the ice cake is thereby discharged. The chains 65 are moved a distance equal to the space between two adjacent shelves 68, thus moving the tilted emptied shelf to the position in 10 which its forward end is supported by the member 95 and placing another shelf with an ice cake 14 thereon in the untilted position shown by broken lines at the bottom of Fig. 6. In the meantime, the cam 82 has operated the connections 78, etc. to place the angle bars 72 in alignment with the guides 71 and support said angle bars rigidly in alignment with said guides and thereby support the lowest loaded shelf 68 untilted. In the specific embodiment of the invention shown, these intermittent operations of the shelves 68 are performed eight times successively, which eight operations empty all of said shelves 68.

Thereupon the motor 22 is operated to move 25 forwardly the foremost series of eight magazines, which forward movement is effected by the arms 37 engaging the projections 44, as already described.

This forward movement of the series of eight 30 loaded magazines causes the ice cakes on said magazines to be swept or removed therefrom by the arms 111 and the ice cakes deposited on the shelves 68. Eventually the arms 37 move out of engagement with the projections 44 and said projections are then engaged by the arms 43 operated simultaneously with the arms 37 and at considerably slower speed in order not to shock or jar the mechanism. The series of magazines that have just been emptied are thereby moved to 40 the rear of the circular series of magazines in the housing, causing the bars 7 and 8 of the emptied magazine to engage the corresponding bars 7 and 8 on the next forwardly adjacent magazine unit and move the entire series of magazines forwardly the width of one magazine unit. 45 Immediately, when the arms 37 and 43 reach their initial starting positions, the motor 22 is stopped until after another series of eight intermittent operations of the motor 46 and the member operated thereby. The mechanism for effecting the automatic starting and stopping of the motor 22 is not herein illustrated or described, and such automatic operation of said motor 22 may be effected and controlled in different ways. 50 The mechanism for controlling and operating said motor 22 is not a part of the present invention.

The time relationship of the effective operations of the several mechanisms of this machine and the effects of such operations are graphically illustrated by Fig. 2. Above the line 121, three related periods of operations are shown. The vertical space below the notation "Eighth discharge cycle" contains a graph 122 designating the positions and movements of the door 19 in an operation of discharging from the machine one of the ice cakes 14. This space also contains a graph 123 designating the positions and movements of the lowermost shelf 68 in an operation of discharging from the machine one of the ice cakes 14. And this space also contains a graph 124 designating the downward or lowering movement of the remaining shelves 68, other than the lowermost shelf 68, on which other ice cakes are supported.

Above the line 121, two additional of the eight

discharge cycles are represented, the remaining five being omitted because they are merely duplications of the cycles designated "First discharge cycle" and "Second discharge cycle", respectively.

The Geneva driving member 53 makes one complete revolution during each operation of the machine to discharge an ice cake, which operation may be controlled by any appropriate type of coin control mechanism, or otherwise as desired. The Geneva driving member 53 and the gear 51, being attached to the same shaft 52, operate at the same time, the gear 51 being rotated by the pinion 50 and thereby rotating the shaft 52 and the Geneva driving member 53. Accordingly, the cam 109, formed on the gear 51, has a definite fixed relationship with the Geneva driving member 53 and, therefore, has a definite starting position. The initial portion of the rotary movement of the cam 109 does not operate the lever 106 and, therefore, the door 19 remains closed during such initial portion of the rotary movement of the cam 109. Thereafter a rise in the cam 109 operates the lever 106 and moves the door 19 upwardly, a high portion of the cam 109 holding the lever 106 in its operated position and thereby supporting the door 19 open for the time and extent of movement of the mechanisms represented by the high part of the graph 122, which is sufficient time for an ice cake 14 to be discharged from the machine by operation of the 25 discharging members 92. Then a descending portion of the cam 109 operates the lever 106 to permit the door 19 to descend, as indicated by the descending portion of the graph 122, and assume its closed and locked position.

These operations have a definite relationship to the operations of the lowermost shelf 68 and the mechanism controlling the tilting thereof. During an appropriate portion of the initial turning movement of the gear 51, on which both cams 109 and 82 are formed, the lever 79 remains unoperated for a longer time than the lever 106 remains unoperated in order to afford time for the door 19 to be opened before the lowermost shelf 68 is tilted. After sufficient time for the 45 door 19 to be opened, the lever 79 is operated by the cam 82 by a quick movement to move the angle bars 72 out of alignment with the guides 71 and thereby permit the lowermost shelf 68 to move from the position, shown by dotted lines in Fig. 6, to the position shown by solid lines. By this, tilting of the lowermost shelf 68 does not occur until after the door 19 has been fully opened, as will be understood by observing that the descending portion of the graph 123 extends beyond 55 the end of the ascending part of the graph 122. The lowermost shelf 68 remains tilted during the time and extent of operation represented by the low portion of the graph 123, after which, as indicated by the rising and horizontal portion of the graph 123, the lowermost shelf 68 moves to the position of that shelf 68 which has its forward end resting on the support 95.

These movements have a definite time relationship and also a relationship in the extent of each operation of the discharging mechanism, including the descending movements of the loaded shelves 68. These relationships are indicated by the relationship of the graph 124 to the graphs 122 and 123.

The effective operation of the Geneva driving member 53 to operate the gearing for operating the chains 65 that support the shelves 68 occurs during the closing movement of the door 19 and while the lowermost shelf 68, from which the 75

ice cake had been moved, remains in its tilted position and continues until after that evacuated shelf has dropped onto the support 95 and during one complete revolution of the Geneva driving member 53.

The time relationship of the operation of re-loading the shelves 68 with ice cakes by operating the chains 29 to move the front tier of magazines 12 across the shelves 68 and cause the arms 111 to sweep the ice cakes from the magazines 12 onto the shelves 68 is indicated by graphic Fig. 2 below the line 121 read in connection with the graphs above the line 121. Beyond the vertical line 125, the door 19 remains closed and the chains 65 and shelves 68 remain stationary. At this time when all of the shelves 68 are empty, the motor 22 begins to operate, thereby operating the chains 29 and causing the arms 37 to engage the projections 44 and thereby move the foremost magazine support 6 and the loaded magazine 12 supported thereby in the direction of the arrow 45 (Fig. 5) and across the shelves 68, causing the arms 111 to stop the ice cakes 14 while the magazines 12 are continuously moved, thereby sweeping the ice cakes from said magazines onto the shelves 68. During this time, the motor 46 and the discharge mechanism of the machine cannot be operated. The discharge mechanism cannot be operated until the magazines just unloaded have been moved beyond possible interference with the proper operation of the discharge mechanism, essentially beyond the arms 111 and to about the position indicated by the line 126. The unloaded magazines are still being moved by the chains 29 and are eventually delivered to the chains 38, the arms 43 engaging the projections 44 after the arms 37 have been moved out of engagement with said projections 44. The single series of magazines that have just been emptied are moved forwardly by the chains 38 until the bars 7 and 8 of said single series of emptied magazines abut against corresponding bars of the next forwardly adjacent series of magazines, after which all of the magazines are moved forwardly one step movement, sufficient to place the foremost series of loaded magazines in position to be engaged by the arms 37 during another operation of the loading mechanism. At this time the motor 22 stops, thereby stopping operation of all of the loading mechanism.

The extent and relationship of movement of the single series of magazines to load the shelves 68 and then to move the emptied magazines onward, as above described, is indicated by the extent of the line below the line indicated by the notation "Movement of single magazine", and the subsequent movement of all magazines to locate another series of loaded magazines in position for a loading operation is indicated by the line below the notation "Movement of all magazines", said designated lines being read in connection with the degree indications in the spaces immediately below the respective lines.

Fig. 10 diagrammatically illustrates a practicable arrangement of the magazines, whereby they may be operated otherwise than along a circular path. The several series of magazines are designated 127 and the arrow line indicates their path of movement other than in a circular direction. The supporting shelves 128 take the place of the supporting shelves 68 and are operated and controlled by mechanisms located in the space 129, which mechanisms may be the mechanisms herein described. An ejector 130, corresponding to the members 92, will be controlled by these

mechanisms at the proper time to eject the ice cakes outwardly into a receiving space 131. The illustration of the operating mechanisms is not here duplicated since they may be easily arranged to perform their intended functions irrespective of whether the magazines move along a circular path, or otherwise. 5

It must now be apparent that this invention is a highly simplified, effective and durable machine that may be controlled in the manner suggested, or otherwise, in order to operate and perform the sequence of operations required to make the machine commercially satisfactory. Safety appliances and devices will be used in connection with the different mechanisms, so that operations 10 of the machine may not be performed as, for instance, when the door 113 is open or when any person is on the inside of the machine. Devices and appliances for these purposes are contemplated but are not illustrated or described in this 15 specification, because such devices and appliances are well known and their embodiment in this machine is entirely practicable and may easily be performed. Without restricting myself in these 20 or any unessential respects, I claim:— 25

1. A vending machine comprising a housing having an outlet opening, mechanism mounted in said housing for individually supporting a vertical row of articles in vertically spaced relationship to be ejected successively through said opening, machinery for operating said mechanism to move the articles successively and intermittently to position for ejection through said opening, vertically spaced devices in said housing for individually supporting a vertical row of articles for placement on said supporting mechanism, and mechanism for operating said devices horizontally and transversely of said supporting mechanism to remove articles therefrom and place said articles on said supporting mechanism. 30

2. A vending machine comprising a housing having an outlet opening, mechanism mounted in said housing for individually supporting a vertical row of articles in vertically spaced relationship to be ejected through said opening, machinery for operating said mechanism to move the articles successively and intermittently to position for ejection through said opening until all of the articles are ejected from said mechanism, vertically spaced supporting magazines in said 35 housing for supporting vertical rows of articles for placement on said supporting mechanism, and mechanism for operating said supporting magazines horizontally adjacent to said first mechanism as required to place said articles on 40 said supporting mechanism. 45

3. A vending machine comprising a housing having an outlet opening, carriers mounted in said housing for individually supporting and successively carrying articles to position to be ejected from said opening, machinery in said housing for operating said carriers and for ejecting articles therefrom through said outlet opening successively and intermittently, and mechanism for placing a plurality of articles on said carriers 60 after a plurality of articles have been ejected. 65

4. A vending machine comprising a housing having an outlet opening, carriers mounted in said housing for individually supporting and successively moving downwardly articles to position 70 opposite said outlet opening, a door for said outlet opening, machinery in said housing for operating said carriers and for opening said door, mechanism for ejecting an article from one of said carriers through said opening after said door 75

has been opened, and mechanism for placing a plurality of articles on said carriers after a plurality of articles have been ejected.

5. A vending machine comprising a housing having an outlet opening, endless chains supported in said housing, carriers pivoted to said chains for supporting and successively carrying articles downwardly to position opposite said opening, means for tilting the lowermost carrier 10 that supports an article opposite said opening, ejectors for ejecting the article from the tilted carrier, and automatic mechanism for replacing articles on said carriers after all articles have been ejected therefrom.

15. 6. A vending machine comprising a housing having an outlet opening, endless chains supported in said housing, carriers pivoted to said chains for supporting and successively carrying articles downwardly to position opposite said opening, means for tilting the lowermost carrier 20 that supports an article opposite said opening, ejectors for ejecting the article from the tilted carrier, means for restoring the carriers to position to receive articles, and mechanism for simultaneously placing a plurality of articles on said carriers to replace the articles that have been removed therefrom.

. 7. A vending machine comprising a housing having an outlet opening, carriers mounted in 30 said housing for supporting and successively carrying articles downwardly to position to be ejected from said opening, machinery in said housing for operating said carriers, ejectors for ejecting articles from said carriers through said outlet 35 opening successively and intermittently, magazines for supporting articles in said housing to be placed on said carriers, mechanism for moving said magazines across said carriers, and devices for removing the articles from said magazines and causing said articles to be deposited on said carriers during movement of said magazines across said carriers.

40. 8. A vending machine comprising a housing having an outlet opening, a door for said outlet opening, a series of carriers mounted in said housing for supporting and successively carrying downwardly to position opposite said outlet opening articles to be ejected through said opening, and means for causing a tilting movement of the 45 carrier that supports an article opposite said opening after said door has been opened.

50. 9. A vending machine comprising a housing having an outlet opening, a door for said opening, a movable series of pivoted carriers supported in said housing for supporting and successively carrying articles to position to be ejected through said opening, and mechanisms for opening said door and then tilting the carrier that supports an article opposite said outlet opening and ejecting the article from the tilted carrier through 55 said outlet opening.

60. 10. A vending machine comprising a housing having an outlet opening, a door for said opening, a movable series of pivoted carriers supported in said housing for supporting and successively carrying articles to position to be ejected through said opening, mechanisms for opening said door and then tilting the carrier 65 that supports an article opposite said outlet opening and ejecting the article from the tilted carrier through said outlet opening, a movable series of supports for articles adjacent to said carriers, and mechanism for operating said supports and removing the articles therefrom and 70

depositing the articles on said carriers from which articles have been ejected as aforesaid.

11. A vending machine comprising a housing having an outlet opening, pivoted carriers supported in said housing for supporting and successively carrying articles to position to be ejected through said opening, guides for supporting said carriers in position to retain articles thereon, a door for said opening, and mechanism for first opening said door and then tilting the 10 carrier that is opposite said outlet opening to position to discharge the article thereon toward said outlet opening and then moving another carrier with an article thereon to position opposite said outlet opening. 15

12. A vending machine comprising a housing having an outlet opening, a vertical series of carriers supported in said housing, machinery in said housing for moving said carriers downwardly successively to position in which the articles 20 on the respective carriers may be ejected through said opening, a vertical series of supporting magazines in said housing, and mechanism for removing articles from said magazines and depositing said articles on said carriers. 25

13. A vending machine comprising a housing having an outlet opening, a door for said opening, a vertical series of carriers in said housing, machinery in said housing for operating said carriers intermittently to move the articles downwardly to locate the articles thereon successively opposite said opening, connections operated by said machinery for opening said door, devices operated by said machinery for ejecting the article from the carrier opposite said outlet opening after said door is opened, and mechanism operating in timed relation to said carriers to place a plurality of articles on said carriers simultaneously after all articles have been ejected therefrom. 40

14. A vending machine comprising a housing having an outlet opening, a door for said opening, a vertical series of carriers in said housing, machinery in said housing for operating said carriers intermittently to locate the articles 45 thereon successively opposite said opening, connections operated by said machinery for opening said door, devices operated by said machinery for ejecting the article from the carrier opposite said outlet opening after said door is 50 opened, a vertical series of supports for articles in said housing, and mechanism for removing articles from said supports and placing said articles on said carriers in substitution for the articles that have been ejected from said carriers. 55

15. In a vending machine, means for supporting vertical tiers of articles for movement around a space, mechanism for moving said supporting means intermittently and delivering articles therefrom, a dispensing mechanism receiving 60 the articles delivered from said supporting means, and means for maintaining a gap between two vertical tiers of articles to provide a passageway for a person to pass into said space.

16. A vending machine comprising a dispensing mechanism, a series of supporting devices for supporting articles to be dispensed, mechanism for moving one of said supporting devices and delivering the articles supported thereby to said dispensing mechanism while the other supporting devices remain stationary, and means for then moving all of the supporting devices to 70 position for subsequent operation. 65

17. A vending machine comprising a series of article supports, a dispensing mechanism for the 75

articles, propelling means for moving one of said article supports to deliver articles therefrom to said dispensing mechanism while the other supporting devices remain stationary, and mechanism for then moving said article supports to position for subsequent operation.

18. A vending machine comprising carriers for supporting and moving articles to a dispensing means, mechanism for operating said carriers, a 10 magazine for supporting articles to be placed on said carriers, mechanism for moving said magazine across said carriers, and devices for removing the articles from said magazine and causing said articles to be deposited on said carriers during movement of said magazine across said carriers.

19. A vending machine comprising a series of article supports, a dispensing mechanism for the articles, propelling means for moving said article supports past said dispensing mechanism, and means for delivering articles therefrom to said dispensing mechanism, said propelling means being adapted to move one of said article supports at a greater speed than the remaining article supports are moved thereby.

20. A vending machine comprising a series of article supports, a dispensing mechanism for the articles, propelling means for moving said article supports past said dispensing mechanism, and 20 means for delivering articles therefrom to said dispensing mechanism, and mechanism cooperating with said propelling means to move one of said article supports a distance greater than the remaining article supports are moved thereby.

21. In a vending machine, a dispensing device, a series of supports for articles to be delivered to said dispensing device, means for moving one of said article supports a distance greater than the remaining article supports are moved thereby 40 past said dispensing mechanism, and means for delivering articles to said dispensing device and to leave said dispensing device unobstructed by said article supports.

22. A vending machine comprising an endless 45 vertical conveyor for moving articles downwardly to a discharge opening, article carriers movable downwardly and upwardly thereby, rigid guides holding said carriers approximately horizontal during downward movement thereof and leaving said carriers free to swing to approximately vertical position during upward movement thereof,

mechanism for operating said conveyor, and mechanism for reloading said conveyor with a plurality of articles simultaneously after articles have been removed therefrom.

23. A vending machine comprising a series of supports for articles to be dispensed, an endless conveyor operating at an angle to the horizontal, pivoted carriers on said conveyor for individually supporting articles, mechanism for operating said conveyor intermittently to move the supported 10 articles downward, means for supporting said carriers approximately horizontally during the descending movements thereof, and mechanism for moving articles horizontally and delivering a plurality of said articles simultaneously to said 15 carriers during the time that said carriers are supported approximately horizontal.

24. A vending machine comprising means for supporting articles, dispensing mechanism including an endless conveyor having article carriers pivoted thereto, means for supporting said article carriers approximately horizontal during descending movement thereof and leaving said carriers free to swing to vertical positions during upward movement thereof, means for moving 20 articles horizontally and delivering a plurality of articles simultaneously to said carriers, and means for moving articles from said carriers in a direction at an angle to said first named movement of said articles.

25. A vending machine comprising a dispensing mechanism for supporting a plurality of ice cakes in vertically spaced relationship, a reloading mechanism for delivering simultaneously to said dispensing mechanism a plurality of ice cakes in 35 said vertically spaced relationship, a member for operating said dispensing mechanism, and a separate member for operating the reloading mechanism to permit the dispensing mechanism to be operated during a part of the time that the 40 reloading mechanism operates.

26. In a vending machine, means for supporting layers of articles around a central space in mutually spaced relation, said means adapted to be refilled with articles from said central space, mechanism for removing a plurality of articles simultaneously from said supporting means and for supporting said articles in spaced relationship, and devices for discharging articles successively from said mechanism.

JOHN H. SCHREIBER.
